UNITED STATES PATENT OFFICE

MANUEL P. MELLO, OF FALL RIVER, MASSACHUSETTS

MACHINE FOR COMBING TEXTILE FIBERS

Application filed March 20, 1931. Serial No. 524,058.

This invention relates to machines for combs textile fibers as a preparatory step in the manufacture of yarn and is intended to provide a construction and arrangement of mechanism by which the combing operation can be more perfectly performed, while at the same time increasing production and improving the quality of the product.

The combing of cotton or similar textile fibers as heretofore practiced has been regarded as too expensive an operation for the ordinary or cheaper grades of goods because of the large percentage of fibers taken out of the lap as it is brought to the comb for treatment, the loss amounting to fifteen to twenty percent of the material to be combed which goes into waste. Heretofore, the best type of combers could not be advantageously operated at substantially above ninety cycles per minute, since speeding up the machine resulted in increase in waste and deterioration of the product.

One of the difficulties lies in providing a drive transmission for the detaching and piecing rolls that will adequately meet the requirements of the case and allow their action to be speeded up and at the same time avoid shock or jerk and maintain the desired smoothness of action while exercising a positive continuously running driving connection to impart the necessary acceleration, retardation and reversing of the detaching and piecing rolls with a properly timed pause. Neither the intermittently acting clutches, nor the continuously rotated variable speed transmission trains heretofore used or tried, have been satisfactory because the former resulted in a sudden jerky action while the latter has not secured the proper timing of the reversing, retarding and pause to properly piece the detached ends of the combed lap together after the half lap needles have passed through the nipper engaged portion of the lap.

One feature of the present invention con-

sists in the use of a reversible differential-speed transmission combined with a suitable controlling cam, which can be precisely formed to give any desired timing and rate of acceleration or retardation of the detaching and piecing rolls, as well as the timing of the reversing and pause thereof, thus permitting the detaching and piecing mechanism and the associated feeding and nipping mechanism to operate at much higher speeds than heretofore was practicable, while at the same time decreasing the percentage of waste and improving the quality of the product.

But while this new transmission for the detaching and piecing rolls makes possible the speeding up of the detaching and piecing mechanism, it would not be practicable to make a corresponding increase in the speed of revolution of the half lap needles or comb teeth through the lap without increasing the stress on the fibers during the combing operation and involving also an undesirable increase in the production of waste. Accordingly, to get the fullest advantage of the increased speed of operation made possible by my improved transmission train, I prefer to use such transmission in conjunction with a cylinder or half lap shaft that carries double sets of half laps and is driven indirectly from the main control shaft through a two to one speed reducing gearing that rotates the half lap cylinder one half revolution for each full revolution of the main control shaft, which controls or times the action of the lap feeding and nipping mechanism although I do not confine the use of my new transmission to this form of driving head alone.

My improvements are so contrived that they may be readily applied to the driving head of a well known type of comb at a minimum of expense without necessitating the rebuilding or changing of other parts of the machine, which is a very important

consideration because of the very large number of such combers now in use and the heavy expense that would be involved in replacing or rebuilding them.

5 In the accompanying drawings I have illustrated so much of the mechanism of the well known Nasmith type of comber, originally patented March 3, 1903, United States Patent No. 724,119 and later modified 10 in details, as may be necessary to a proper understanding of my invention as applied thereto.

In the drawings

Fig. 1 is a plan view of the driving head 15 of the Nasmith type of comber containing my aforesaid improvements.

Fig. 2 is an end elevation, partly in section, showing the double half lap arrangement in conjunction with the nipper and 20 feeding mechanism and the detaching and piecing rolls.

Fig. 3 is a central section through the reversing variable speed transmission element.

Fig. 4 is an end elevation showing the 25 train of gearing through which rotative movement is transmitted from the differential to the detaching and piecing rolls on plane X—X of Fig. 1.

Fig. 5 is an end elevation on plane Y—Y 30 of Fig. 1 showing my improved transmission train for controlling and timing the operation of the detaching and piecing rolls through the differential.

Fig. 6 is an end elevation on plane Z—Z 35 of Fig. 1 showing the speed reducing train for driving the half lap cylinder from the control shaft.

In Fig. 1 I have shown a plan view of the driving head of the Nasmith type of comber 40 equipped with my improved transmission control.

The power shaft 1, equipped with the usual driving pulleys, is located in the two spaced standards M and O of the machine and is 45 provided with a pinion 2 gearing into a large pinion 3, that is secured to the timer control shaft 4 to which is secured a pinion 6 intermeshing with a back pinion 8, which is compounded with a smaller back pinion 9 to 50 intermesh with a pinion 10 that is secured to an annular flanged member 11 on the cylinder shaft or half lap shaft 12 to which the cylinder or drum 13 is secured which carries the series of half laps 14 embracing the usual 55 combing needles and, in the present case, whose individual members are diametrically opposed to each other. Only the first pair of half laps 14 are shown in the drawings as the others, however numerous, are mounted 60 in the same way and act in the same manner.

It will be noted that the back gearing pinions 8 and 9 are mounted on a shaft carried by a bearing bracket 7, that is attached to the usual frame work of the machine. 65 Furthermore, the ratio of this added set of

pinions is such that the pinion 10, secured to the cylinder shaft 12, rotates half the number of revolutions as does the time controlled shaft 4 and the initial pinion 6 of this back gearing train, which rotates the 70 half lap cylinder. This interposition, therefore, of the speed reducing gearing at this point acts to produce a half revolution of the cylinder for each complete revolution of the time controlled shaft, while the feeding 75 and nipping mechanism and the detaching and piecing roll mechanism perform one complete operation at each complete revolution of the time control shaft 4.

The time control shaft carries at its outer 80 end the usual regulating or setting dial wheel 23 beneath the pointer 23^a, which has a projecting pin engaging a slide box 21 on the lever 22, which is secured to the rock shaft 20 to cause oscillation thereof in accordance 85 with the timing established by the adjustment of the dial wheel 23. This rock shaft 20 carries a lever 31 through which suitable actuation of the well known nipper mechanism, partly illustrated in Fig. 2, is actuated 90 and controlled.

Secured to the time control shaft also is the usual eccentric 25 surrounded by the head 95 of the eccentric lever 25^a, which at its rear end is connected with an arm 26 on the rock shaft 27, to which is secured another arm or lever 28 having a link rod connection 29 in the usual manner to actuate the top roll of the first pair of detaching rolls in order to cause said roll D¹ to travel bodily around the 100 periphery of the positively driven bottom detaching roll D.

It has been customary in these machines to operate the detaching and piecing rolls through actuating mechanism embracing intermittently engaged clutch members. It has also been proposed to rotate the detaching rolls by means of a train of mechanism including an epicyclic differential speed device actuated by elliptical gears, but each method of actuating the detaching rolls has been found unsatisfactory. The intermittent clutch connections impart a sudden jerky movement where a smooth movement is extremely desirable to effect good results in piecing up the detached ends of the lap, while on the other hand the elliptical gear drive for the epicyclic differential transmitting element does not permit the appropriate timing of the reversing of the detaching and piecing rolls to give the proper overlapping of one detached tuft upon the other when piecing together the lap. 115

One feature of my present improvement 120 is that it affords a means for perfectly timing the two reversing movements of the detaching and piecing rolls, so that each successive detached tuft can be overlapped or deposited on the next preceding tuft presented to it so as to give precisely the right amount of 130

overlap, namely, substantially one-half the length of each tuft to produce a uniform and even combed lap as it is delivered from the machine.

5 In the form of transmission herein illustrated I mount loosely on the nipper shaft 20 a sector arm 40, whose sector teeth 40^a intermesh with a pinion 43 fast on the internal shaft 44 of the epicyclic transmission 10 element 45. This sector arm 40 carries a laterally projecting bowl 41, which engages the groove 42^a of a groove or runway in the lateral face of a cam 42 that is secured to the timer control shaft 4. Since the epicyclic 15 differential transmission 45 is a well known mechanical device, I have shown the details of construction only by the cross sectional view in Fig. 3. As there shown, the interior shaft 44, which carries the sector arm engaged 20 pinion 43, extends through the housing or casing 46 and through two axially aligned bevelled gears 47 and 49, the former of which is fast to the shaft 44 and constitutes the interior driving element of the differential, while the latter 49 is loose on the shaft 44. Mounted on a central diametrical axis are idler bevelled gears 48 which intermesh with bevelled gears 47 and 49 to transmit the motion of one to the other. The 25 casing or housing 46, in which these four bevelled gears are mounted, is provided with a peripheral gear ring 46^a arranged to intermesh with the pinion 6 on the timer control shaft 4.

30 In order to aid an understanding of the action of my improved transmission I will briefly describe the well known operation of the feeding and nipping mechanism in conjunction with the half lap, the top comb and the detaching and piecing rolls, having particular reference to the mechanism shown in Fig. 2.

35 Lap over fiber that is to be combed is in the form of a film or lap, usually twelve inches wide, coiled into a roll which rests on the usual revolute supporting roll not here shown, whose revolution permits the lap to unwind without strain and pass down over the nipper bed or plate 33 and beneath the feed roll 30 carried by the oscillating nipper frame 32. The nipper frame is oscillated from the nipper shaft 20 through lever 31 and connecting link 31^a. The upper nipper or blade 34 pinches or grips and holds the advanced portion of the lap so that the forwardly projecting tuft thereof is held while the rows of needles of the half lap are combing through it.

40 According to the showing of Fig. 2 the half lap has just completed the combing of the tuft, its heel or rear portion passing by the nippers. At this stage the top roll D¹ starts to travel forward from its rear-most position and the rolls are ready to start their reverse rotation to feed the previously

50 combed stock backward into position to be overlapped by the advancing tuft that has just been combed. Next, the nippers begin to open while advancing toward the detaching and piecing rolls D, D¹. The rolls then 55 rotate in a forward direction, the top comb 35 being moved down to penetrate the advancing tuft. The rate of movement of the parts, of the pause or dwell given to the mechanism should be such that the newly 60 combed tuft overlaps for about half its length the previously combed tuft, so that the film of cotton forming the sliver issuing from the second pair of rolls D², D³ will be 65 of uniform double thickness.

70 It is the timing of the action of the detaching and piecing rolls that is controlled adequately by my improved detaching roll control and actuating mechanism.

75 As viewed from the right hand end in Fig. 1, the main control shaft 4 rotates continuously in a counterclockwise direction, thus producing a rotation of the epicyclic differential 45 in a clockwise direction. If the pinion 43 and the shaft 44 be held stationary, the pinion 50 will also rotate in a clockwise direction and is fast on the hub or sleeve 49^a of the bevel pinion 49. If the pinion 43 be rotated by the upward movement of the sector arm 40 in a counterclockwise direction, it 80 will accelerate the clockwise rotation of the pinion 50, the degree of acceleration depending upon the speed of movement of the sector arm in its upward travel. The pinion 43 85 may be rotated in a clockwise direction by the downward movement of the sector arm at a sufficient rate of speed to cause reverse or counterclockwise rotation of the pinion 50. Since the cam 42 may be cut or formed to give any desired rate of travel in either direction and any desired length of pause to the movement of the sector arm, it will be understood that a perfect control may be established to give the detaching and piecing rolls 90 any desired timing as to forward and backward rotation and any desired rate of retardation or acceleration and any desired degree of pause in their various movements, thereby permitting the perfect coordination of the detaching and piecing rolls with the combing 95 and nipper mechanism, while at the same time maintaining a positive connection and control, with the timing shaft, which is continuous and uninterrupted. This results in a smooth non-jerky action of the detaching 100 and piecing rolls so that their operation may be very substantially speeded up without producing imperfect work.

105 In Fig. 1 and Fig. 4 is illustrated the positive driving and control connection between the detaching and piecing rolls. This train of gearing embraces a pinion 51 meshing with pinion 50 by which it is actuated and controlled and compounded with a double width pinion 52 which intermeshes with pinions 53 and 54 110

for driving the piecing and detaching roll shafts.

The rotation of the double half lap cylinder shaft through a 50% speed reducing train makes it possible to give the cylinder shaft a speed of approximately sixty-five revolutions per minute as against ninety revolutions per minute, thus making possible the feeding of a much heavier lap through the comb because of this diminished speed, while, by reason of the fact that there is a combing of the fiber at each half revolution of the cylinder shaft, there is obtained at the aforesaid speed of the cylinder shaft about one hundred and thirty complete combing operations per minute which, coupled with the increased weight of the lap that can be fed to the machine, results in an increase of production of approximately 100%, while at the same time securing more perfect combing action and a considerable decrease in the ratio of waste fiber, while the combed fibers are subjected to much less stress and strain because of the relatively slow movement of the comb needles through the lap in the combing operation.

Furthermore, these great advantages are secured through a comparatively simple change in the head of the machine alone, since it requires disconnecting at the head, the time control shaft from the cylinder shaft and inserting the back train gearing bracket with the back train pinions for reducing the speed ratio between these two shafts one-half, while the sector arm and its pinion can be readily inserted with a properly cut cam secured to the time control shaft, as described.

What I claim is:

1. A driving head for a comber embracing in combination a driving and controlling shaft, a separate revoluble comb cylinder shaft carrying pairs of diametrically opposed half-laps, a gear connection between said shafts for driving the latter shaft one-half revolution for each revolution of the former, a differential speed transmission comprising a continuously revolving member rotated at constant speed by connection with the driving shaft, and an oscillatory variable speed member continuously and positively controlled by a lever and cam actuating connection with said driving shaft for positively controlling and producing forward and back rotation at different speeds, of piecing and detaching rolls, and means controlled and actuated by said drive shaft to operate lap feeding and nipping means through a complete cycle at each revolution of the drive shaft.

2. In a driving head for a comber the combination with a revoluble comb cylinder shaft carrying pairs of diametrically opposed half-laps, a separate drive shaft arranged coaxially of said cylinder shaft and having driving connection therewith through a two-to-one speed-reducing gearing, a speed-change

reversing transmission unit, one member of which is continuously revolved at uniform speed by driving connection with said drive shaft, the other member being continuously and positively controlled by a cam and lever connection with said drive shaft to impart forward and back differential speed rotation with predetermined pause to piecing and detaching rolls at each revolution of the drive shaft.

In witness whereof, I have subscribed the above specification.

MANUEL P. MELLO.
